UNITED STATES PATENT OFFICE.

LEROY FARNUM, OF SWAMPSOOTT, MASSACHUSETTS, ASSIGNEE TO UNITED SHOE MACHINERY COMPANY, OF PATERSON, NEW JERSEY, A CORPORATION OF NEW JERSEY.

BUTTONING-MACHINE.

1,207,731.

Specification of Letters Patent. Patented Dec. 12, 1916.

Application filed March 11, 1913. Serial No. 753,522.

To all whom it may concern:

Be it known that I, LEROY FARNUM, a citizen of the United States, residing at Swampscott, in the county of Essex and State of Massachusetts, have invented certain Improvements in Buttoning-Machines, of which the following description, in connection with the accompanying drawings, is a specification, like reference characters on the drawings indicating like parts in the several figures.

This invention relates to buttoning machines.

It is the broad object of the invention to devise a machine that will perform buttoning operations rapidly, without liability of injuring the work and in a generally satisfactory manner.

It is a further object of the invention to devise a machine of this character that will be simple in construction and comparatively inexpensive to manufacture.

For purposes of explanation the invention will be herein disclosed as embodied in a machine for buttoning the uppers of shoes. In the manufacture of button shoes it is the usual practice to button several of the lowermost buttons of the upper before the assembling and lasting operations in order to facilitate the proper lasting of the shoe and to insure the correct positioning of the button piece and buttonhole fly in the finished shoe. This buttoning operation is at the present time performed almost universally by hand operators with the aid of common button hooks.

A more specific object of this invention therefore is to devise a machine that will perform satisfactorily this buttoning operation on the uppers of shoes.

It is customary to button only the buttons on the instep portion of the upper prior to the lasting operation and the number of buttons on this part of the shoe usually varies from three to seven depending on the size and pattern of the upper. Accordingly, in the embodiment of this invention hereinafter to be described in detail, the machine is designed to perform simultaneously the required number of complete buttoning operations necessary to prepare an upper for the assembling and lasting operations. In other words, the machine is of the "gang" type. It should be understood, however, that the in-

vention is not limited to a machine of this type but that many of its features are equally applicable to a machine of the step by step type.

An important feature of this invention resides in means for manipulating the button to present it edgewise to the buttonhole in the buttoning operation. By this arrangement the machine is enabled to effect the relative passage of the button head through the buttonhole with less stretching of the buttonhole and, consequently, with less liability of tearing the buttonhole fly and less distortion of the upper than otherwise would be possible.

Other features of the invention will be readily understood from the following description when read in connection with the accompanying drawings and the novel features will be particularly pointed out in the appended claims. It is to be understood, however, that while this specification describes a machine adapted particularly for buttoning shoes, this description is given by way of illustration rather than limitation and that many of the features of the invention are applicable to machines designed for operating on other classes of work.

Referring now to the accompanying drawings, Figure 1 is a view in front elevation of a buttoning machine embodying this invention in its preferred form, parts of the frame being broken away in order to show more clearly certain details of construction; Fig. 2 is a vertical sectional view on the plane indicated by the line 2-2 in Fig. 1; Fig. 3 is a plan view of the machine shown in Fig. 1 with the cover of the machine cut away; Fig. 4 is a perspective view showing the detailed construction of the parts that operate on a button and buttonhole to perform a buttoning operation; and Figs. 5 to 14 inclusive are a series of plan views, partly in section, of one set of buttoning instrumentalities showing the parts in the successive positions that they occupy in one complete cycle of operations.

The operating parts of the machine are contained in and supported by a frame 2 having an open top that is normally closed by a cover 4, this cover being pivoted at 6 to enable it to swing backwardly to expose the operating mechanism.

The machine comprises a plurality of sets of operating instrumentalities, each set being constructed to effect that relative movement of a button and a buttonhole fly that is commonly termed "a buttoning operation." In the illustrated machine seven such sets are employed since this is the maximum number of buttons that usually are buttoned on a shoe prior to the assembling and lasting operations. Each of these sets of operating instrumentalities includes a frame member 8 which supports the other parts of the set, and all the frame members of the series are mounted for sliding movement toward and from each other on four stationary rods 10, 11, 12 and 13 that extend transversely of the machine frame 2 and are supported in its side walls. Since the several sets are substantially duplicates with the exception of some slight differences in the adjacent frames, to which reference will be made later, it is necessary to give a detailed description of one set only.

Each set consists of a buttoning means and a work receiving means in which the work is initially arranged for its presentation to the buttoning means. Considering first the buttoning means and referring particularly to Figs. 2 and 4 to 14 of the drawings, it will be seen that the frame member 8 has a pair of depending lugs in which is loosely supported a horizontal tubular sleeve 14. A second sleeve 16 telescopes within the sleeve 14 and these two sleeves constitute supports for a pair of thin spring tongs 18, the two tong members being secured by screws 20 to the forward ends of the respective sleeves. The tongs extend forwardly from the machine in a horizontal plane and have shank portions that are bent toward each other sufficiently to overlap at a point a short distance in front of the ends of the supports 14 and 16; and from this overlapping point the tongs bend slightly away from each other again and extend forwardly to form button positioning or holding portions that normally lie side by side and in contact with each other. Each of these button holding portions is apertured as best shown at 22 (Fig. 4), each aperture being shaped to admit the side or edge of a button head so that, when the tongs are spread apart and a button is inserted between them with its head in an inclined or vertical plane, the tongs will embrace opposite sides of the button head and through their spring action will hold the button between them. The tongs normally are closed as shown in Figs. 4 and 5, and in this position they may readily enter a buttonhole and support the buttonhole fly, the button fly being positioned on the shank portions of the tongs back of the button holding portions. In order to spread the tongs apart for the reception of the button head, a

spreader 24 is mounted between the converging shank portions of the tongs and is supported by a rod 26 that slides or telescopes within the tong supporting sleeve 16. This spreader is beveled suitably for engagement with the tongs so that, by moving forward with relation to them, its contact with their converging shank portions will result in wedging the tongs apart as indicated in Figs. 6 to 13.

The buttoning means also includes a buttonhole fly engaging member 28 having a horizontal shank portion that is adjustably secured in the frame 8 by means of a set screw 30 and a depending finger portion 32 located at one side of and close to the tongs 18 in position to bear against the buttonhole fly during the buttoning operation.

The work receiving means comprises a button holding hook 32 positioned in front of and in alignment with the buttoning means, and this hook has a shank which is bent backwardly and is secured to the forward end of a plunger 34 that is mounted to slide in a bore formed in the frame member 8 above and parallel with the tong support 14. A coiled spring 36 positioned within the bore encircles a reduced extension of the plunger and operates to hold the plunger yieldingly at the extreme limit of its forward movement, the extent or limit of this movement being determined by a pair of lock nuts 38 threaded on the reduced portion of the plunger where it projects through the rearward end of the frame member 8. Any turning movement of the plunger in its bore is prevented by a set screw 40 threaded through the frame member and entering a longitudinal groove formed in the plunger. Adjustment of the button receiving hook 32 relatively to the tongs 18 is permitted by bending the end of the shank portion of the hook into the form of a loop and securing this loop to the end of the plunger 34 by means of a screw 42 having its head bearing on both sides of the loop.

The supports 14, 16 and 26 for the tongs and spreader are arranged for longitudinal movement independently of each other; and in order to cause all the sets of buttoning instrumentalities to operate simultaneously, the like supports of all the sets are connected together for common movement. For this purpose each of the supports 14 has a clamp 44 fixed thereto near its rearward end and these clamps are all slidably mounted on a rod 46 that extends transversely of the machine and has its ends supported in the arms of a yoke 48. This yoke slides longitudinally of the machine on a stationary bar 50, that extends longitudinally through the center of the machine frame, and on guideways 52 formed on opposite walls of the machine frame 2 and extending parallel to the bar 50. Motion is imparted to this yoke

by means of a roll 54 journaled thereon and running in a cam way 56 cut in the surface of a barrel cam 58, this cam being loosely mounted for rotation on a shaft 60 that is journaled in the lower part of the machine frame. In like manner the tong supports 16 of the several sets are each provided with a clamp 61 slidably mounted on a transverse rod 62 which is supported by the arms of a yoke 64 mounted on the guideways 52 and bar 50 and carrying a cam roll 65 running in a cam groove 66 in the cam 58. The plunger supports 26 also each have a clamp 67 similar to the clamps 44, the clamps 67 being adjustably mounted on a transverse rod 68 supported in the arms of a yoke 70 that slides on the bar 50 and guideways 52 and carries a roll 71 engaging a cam way 72 in the barrel cam 58. For manufacturing convenience the cam 58 may be made in three sections with one cam way in each section.

By causing the cam 58 to make a single revolution, the yokes 48, 64 and 70 will be moved on the guideways 52 and bar 50 in accordance with the designs of the respective cam ways 56, 66 and 72 and the motion thus imparted to the yokes will be transmitted through the rods 46, 62 and 68 to the respective sets of tong and spreader supports 14, 16 and 26 causing the like supports to move simultaneously. The cam 58 may be driven through any suitable form of single revolution clutch, as for instance one of the type well known in shoe machinery as the Davey clutch, or a similar form known as the Horton clutch. In the arrangement shown the driving shaft 74, which is journaled in the machine frame, has a pulley 76 fast thereon to which power may be supplied from any suitable source; and this shaft carries a worm 78 meshing with a worm gear 80 that is pinned to and drives the shaft 60. The drawings, and more especially Fig. 2, show a clutch of the Davey type interposed between the shaft 60 and the cam 58. This clutch normally holds the cam 58 stationary in a predetermined position but through connections with a treadle 82 (Fig. 1) it may be operated to cause the cam to make a single revolution and then to stop again in said position. Inasmuch as the specific construction of this clutch forms no part of the present invention, a detailed description of it is unnecessary. A ball thrust bearing 84 is mounted between the end of the cam 58 opposite the clutch and the bearing for the shaft 60 to eliminate excessive friction, which otherwise might be caused by the thrust of the clutch mechanism.

The operations performed by each set of operating instrumentalities upon the rotation of the cam 58 will be best understood by referring to Figs. 4 to 14 inclusive. The work first is placed in the machine in the manner indicated in Fig. 2, with the tongs

18 entering and positioning the buttonhole for the buttoning operation and the eye of the button slipped into the inclined opening of the button receiving hook 32 where it is held by gravity with the plane of the button head approximately vertical or slightly inclined. The work being properly placed in the machine the treadle 82 next is depressed tripping the clutch mechanism and causing the rotation of the cam 58 to begin. At the instant when the cam starts the buttoning parts are in the positions in which they are shown in Fig. 5 but immediately thereafter the spreader 24 is moved forward relatively to the tongs and its contact with the converging shank portions of the tongs forces them apart as indicated in Fig. 6. Before this relative movement of the spreader and tongs is completed, the tongs both begin to move forwardly toward the button that is held in the hook 32; and this movement of the several parts continues until the tongs have arrived in the position in which they are shown in Fig. 7, where they are spread apart to their maximum extent and lie at opposite sides of the button head. The spreader 24 then begins to withdraw; whereupon the tongs spring toward each other as rapidly as the spreader permits, and grasp the button with the sides of the button head entering the apertures in the button holding portions of the tongs. In this position the button is firmly held between the tongs, each side of the button head being embraced by one of the tongs. (See Fig. 8).

After the spreader 24 has completed its retracting movement, the outside sleeve or tong support 14 begins to move backward relatively to the other tong support 16, thus withdrawing one tong relatively to the other and causing the tongs to tip the button somewhat as indicated in Fig. 9. While the tongs hold the button in its tipped position both tongs 18 and the spreader 24 are moved backwardly together causing them to withdraw from the buttonhole and to carry the button head edgewise into the buttonhole. The finger 28 remains stationary during this operation and supports the buttonhole fly adjacent to one edge of the buttonhole against the drag exerted on the fly by the button head. The edge of the button adjacent to the finger 28 enters the buttonhole first and the finger 28 presses the material at this edge of the buttonhole under the button head while the material at the other edge of the buttonhole is being bent slightly backward by the drag or pressure of the other side of the button head. The relative positions of the parts at this step in the operation are indicated approximately in Fig. 10. The buttoning operation is now substantially complete so far as one side of the button head is concerned and the but-

ton is next given a tipping movement opposite to the direction of the first tipping movement to carry the other edge of the button past the edge of the buttonhole. This movement is effected by moving the inner sleeve or tong support 16 backward relatively to the outer sleeve 14, the spreader 24 also being moved back to avoid spreading the tongs at this time. This movement tips the button head entirely through the buttonhole, frees the sides of the button head from contact with the edges of the buttonhole and straightens the button, leaving the parts in substantially the positions indicated in Fig. 11. It should be noted that during the entire operation just described the button receiving hook 32 maintains its initial engagement with the work but moves backwardly with the tongs as they carry the button through the buttonhole, the yielding mounting for the hook supporting plunger 34 permitting this movement. Since the button receiving hook 32 is open for the entrance or removal of the button in a direction transverse to the direction of the withdrawing movement of the tongs, their action on the button has no tendency to release the button from the hold of the hook.

The button head has now been drawn entirely through the buttonhole and the next step is to free the button from the buttoning mechanism. This operation is effected by advancing the spreader 24 relatively to the tongs 18, thus spreading the tongs apart and causing them to release the button, (see Fig. 12), whereupon the spring 36 immediately forces the button hook supporting plunger 34 forward causing the hook to carry the work away from the tongs (see Fig. 13). Upon the withdrawal of the spreader to its retracted position, all the parts are again placed in their initial positions ready for the next buttoning operation. The work is removed from the machine by a movement opposite to the inserting movement, that is, by lifting it upwardly in a direction inclined toward the left out of the button receiving hook 32 and then dropping it away from the hook. It will be understood, of course, that the movements of the tong supports 14 and 16 and of the spreader support 26 and the consequent movements of the parts carried by these supports, are controlled by the designs of the respective cam ways 56, 66 and 72.

An important advantage of tipping the button to present it edgewise to the buttonhole in the manner above described is that it avoids spreading the buttonhole as much as otherwise would be necessary in the buttoning operation, and thus avoids possible damage to the buttonhole fly and the introduction of wrinkles into the stock that would

have to be ironed or smoothed out at a later stage in the manufacture of the shoe. It should be noted also that by the novel construction of the shank portions of the tongs excessive spreading of the buttonhole is avoided when the tongs are spread apart. The extreme simplicity of the buttoning instrumentalities will be readily appreciated.

The spacing of the buttons and buttonholes varies on different sizes and patterns of uppers and it is for the purpose of enabling the sets of operating instrumentalities to be adjusted in accordance with this spacing that they have been mounted for movement toward and from each other on the rods 10 to 13 inclusive as above described. This adjustment of the sets is effected by means of a lazy-tongs mechanism 88 (see Figs. 2 and 3) that is arranged below the supporting frames 8 and has its series of middle pivots 90 connected respectively to the frame members 8. The lazy-tongs mechanism is operated by means of a rod 92 which extends loosely through the entire series of frame members 8 and is journaled in the walls of the machine frame 2, this member being provided near its opposite ends with right and left hand threaded portions 93 and 94, respectively, that have threaded engagement with the two outside members 8 of the series. One end of the rod is provided with a handle 96 by means of which it may be turned conveniently. It will be evident that, when the rod 92 is turned, the two outside members 8 will be moved toward or from each other depending upon the direction of this turning movement, and through the contraction or expansion of the lazy-tongs mechanism produced in this manner, this adjusting movement will be transmitted to all the other members 8 of the series with the exception of the middle member which will remain stationary. This arrangement also serves to hold the several sets of buttoning instrumentalities in adjusted relationship to each other. The sliding engagement of each series of clamps 44, 61 and 67 with its respective supporting rod 46, 62 and 68 permits the adjusting movement of the sets of buttoning instrumentalities relatively to each other without disturbing their connections with the cam 58.

The two outside members 8 and the middle member are each supported on the rods 10 and 13. The second and fifth of these members, referring particularly to Fig. 3, and counting from the bottom, are supported on the rods 10 and 12; and in order to avoid any possibility of these members binding during their adjusting movement they are each provided with an elongated boss or hub 97 through which the supporting rod 12 extends. These hubs afford a long bearing for the members 8 on the rod 130

12, and the adjacent members 8 are recessed to admit the hubs as the members slide toward each other. Similarly, the third and sixth members 8 of the series are mounted on 5 the rods 11 and 13 and are provided with hubs like the hub 97 to slide on the rod 11.

From the foregoing description, the operation of the machine as a whole will now be readily understood. The operator first 10 determines the number of buttons that are to be buttoned on each upper and if he finds this number to be less than seven (the number of sets of operating instrumentalities in the machine) then he removes from each 15 of the sets that are found to be unnecessary for the particular work at hand the button receiving hook 32, the fly engaging finger 28 and the tongs 18. He next turns the handle 96 to adjust the spacing of the 20 sets to agree with the spacing of the buttons and buttonholes on the work. The machine is then ready for the introduction of the work and for this purpose the operator grasps an upper in both hands and presents 25 it to the buttoning means in a substantially vertical plane, entering the several pairs of tongs 18 in the series of buttonholes with which the buttons are to be engaged. The button holding portions of the tongs 18 30 prevent the buttonhole fly from slipping off the tongs and the fly engaging fingers 28 limit the backward movement of the buttonhole fly on the tongs. The button piece is then grasped and turned so that the row of 35 buttons projects toward the machine and the button piece is given a downward diagonal movement toward the right to slip the button shanks into the openings of the button receiving hooks 32. The operator 40 next depresses the treadle 82 tripping the clutch and setting the cam 58 in motion; whereupon all the sets of operating instrumentalities perform simultaneously the cycle of operations above described with particular reference to Figs. 4 to 14, inclusive. 45 That is, the several pairs of tongs advance together, grasp the buttons held by the hooks 32, tip them edgewise simultaneously toward the buttonhole fly and withdraw, 50 carrying the button heads edge foremost into their respective buttonholes; then they straighten the buttons simultaneously, and finally spread apart to release the buttons. After the buttoning operation has been completed 55 the upper is left suspended in the work receiving hooks 32 and it is removed from the machine by giving it an upward diagonal movement toward the left to clear each button from its receiving hook 32 and 60 then moving the upper downwardly out of contact with the hooks. The clutch automatically stops the machine with the parts in their initial positions ready for the presentation thereto of another upper.

65 Having thus described my invention,

what I claim as new and desire to secure by Letters Patent of the United States is:—

1. In a buttoning machine the combination of means for initially positioning a button, means for engaging the button in 70 said positioning means, buttonhole fly engaging means, and mechanism for relatively moving the button engaging means and the buttonhole fly engaging means to effect a buttoning operation, said mechanism being 75 constructed to cause the button to be tipped during said buttoning operation to present it edgewise to the buttonhole.

2. In a buttoning machine the combination of means for initially positioning a 80 button, means for engaging the button in said positioning means, buttonhole fly engaging means, and mechanism for relatively moving said button engaging and fly engaging means to effect a buttoning operation, 85 said mechanism being constructed to impart to the button a plurality of tipping movements during the buttoning operation.

3. In a buttoning machine the combination of button holding means movable to 90 grasp a button, buttonhole fly engaging means, and mechanism for causing said holding means to tip the button to present it edgewise to the buttonhole and for relatively moving said button holding and buttonhole fly engaging means to complete the 95 buttoning operation.

4. In a buttoning machine the combination of button holding means comprising a plurality of devices constructed to engage 100 different portions of a button, buttonhole fly engaging means, and mechanism for moving said devices relatively to each other to tip the button and for effecting a relative movement of said button holding and fly 105 engaging means to complete the buttoning operation.

5. In a buttoning machine the combination of button holding means constructed to engage a button at opposite sides of the 110 button head, buttonhole fly engaging means, and mechanism for causing said holding means to tip the button to present it edgewise to the buttonhole and for relatively moving said button holding and fly 115 engaging means to complete the buttoning operation.

6. In a buttoning machine the combination of opposed button holding devices constructed to engage opposite sides of a button head to hold the button between them, buttonhole fly engaging means, and mechanism for relatively moving said means and devices to effect a buttoning operation.

7. In a buttoning machine the combination of work holding means constructed to hold a button and to enter and position a buttonhole, additional means to engage the buttonhole fly, and mechanism for relatively moving said work holding and fly engaging 125 130

means to present the button edgewise to the buttonhole and to complete the buttoning operation.

8. In a buttoning machine the combination of work holding means constructed to support a button and to enter and position a buttonhole, buttonhole fly engaging means, and mechanism for causing said work holding means to tip the button to present it edgewise to the buttonhole and for relatively moving said work holding and fly engaging means to complete the buttoning operation.

9. In a buttoning machine the combination of a pair of button holding tongs constructed to engage opposite sides of a button head to hold the button between them, said tongs being constructed to enter and position a buttonhole, buttonhole fly engaging means, and mechanism for relatively moving said means and tongs to effect a relative passage of the button head through the buttonhole, said mechanism being constructed to move said tongs relatively to each other to tip the button to present it edgewise to the buttonhole.

10. In a buttoning machine the combination of button holding means, buttonhole fly engaging means, and mechanism for relatively moving said holding and fly engaging means to effect a buttoning operation, said mechanism being constructed to tip the button to present it edgewise to the buttonhole and to straighten the button again after it has entered the buttonhole.

11. In a buttoning machine the combination of button holding means, buttonhole fly engaging means, and mechanism for relatively moving said button holding and fly engaging means to effect a buttoning operation, said mechanism being constructed to cause the button to be tipped during the buttoning operation to facilitate the disposal of the edges of the buttonhole under the button head, and said fly engaging means being constructed to resist the drag of the button on the buttonhole fly during said buttoning operation.

12. In a buttoning machine the combination of button holding means, buttonhole fly engaging means, and mechanism for relatively moving said holding and fly engaging means to effect a buttoning operation, said mechanism being constructed to cause said holding means to tip the button during its relative passage through the buttonhole and to release the button after the buttoning operation has been completed.

13. In a buttoning machine the combination of a pair of button holding tongs constructed to support the head of a button between them and to enter and position a buttonhole, buttonhole fly engaging means, and mechanism for moving said tongs to cause the tongs to withdraw from the buttonhole and carry the button head through the but-

tonhole, said fly engaging means operating to support the buttonhole fly adjacent to the buttonhole during said movement of the tongs, and means for operating the tongs to cause them to release the button after the buttoning operation has been completed.

14. In a buttoning machine the combination of a pair of button holding tongs constructed to embrace opposite sides of the head of a button to hold the button between them and adapted to enter and position a buttonhole, buttonhole fly engaging means, and mechanism for relatively moving said means and tongs to withdraw the tongs from the buttonhole and to carry the button head through the buttonhole, said mechanism being constructed to move one of the tongs ahead of the other during such relative movement to tip the button edgewise toward the buttonhole and thereafter to effect a further relative movement of the tongs to straighten the button.

15. In a buttoning machine, a pair of thin, opposed tongs constructed to enter a buttonhole and having portions shaped to embrace opposite sides of a button head to enable the tongs to hold the button between them.

16. In a buttoning machine, a pair of tongs constructed to enter a buttonhole, said tongs having shank portions adapted to position the buttonhole and button holding portions constructed to embrace the opposite sides of a button head to hold the button between them, and means for spreading said tongs apart to enable them to receive or release the button head, the shanks of said tongs being constructed to avoid excessive spreading of the buttonhole.

17. In a buttoning machine, a pair of opposed tongs constructed and arranged to engage opposite sides of a button head, said tongs being constructed also to enter a buttonhole, and each tong having an aperture of sufficient size to receive a portion of the button head to permit the tongs to hold the button in the buttoning operation without requiring excessive spreading of the material at the edges of the buttonhole.

18. In a buttoning machine, a pair of tongs of resilient material normally positioned side by side and each having an apertured portion, said portions being adapted to embrace opposite sides of a button head to hold the button between them, and means for spreading said tongs apart to enable them to receive or release the button.

19. In a buttoning machine, a pair of tongs constructed to engage opposite sides of a button head to hold the button between them, and means for relatively moving said tongs to tip the button.

20. In a buttoning machine, a pair of tongs positioned side by side and shaped to embrace opposite sides of a button head, in-

dependent supports for said tongs mounted for movement in directions parallel with each other, and operating mechanism for moving said supports together and for moving one support relatively to the other.

21. In a buttoning machine, a pair of tongs positioned side by side and constructed to embrace opposite sides of a button head to hold a button between them, 10 means for spreading said tongs apart to enable them to receive or release a button, and means for moving one of said tongs relatively to the other to cause the tongs to tip the button.
- 15 22. In a buttoning machine, a pair of tongs positioned side by side and constructed to engage opposite sides of a button head to hold a button between them, independent supports for said tongs mounted 20 for movement in directions parallel with each other, a spreader arranged to engage said tongs to move them apart for receiving or releasing a button, and operating mechanism for moving said supports together and 25 relatively to each other.

23. In a buttoning machine, a pair of tongs positioned side by side and constructed to engage opposite sides of a button head to hold the button between them, 30 independent supports for said tongs, a spreader positioned for engagement with said tongs, a support for said spreader, the supports for said tongs and said spreader having a telescopic engagement with each 35 other, mechanism for operating said spreader support to cause the spreader to move the tongs apart, and mechanism for operating said tong supports to move the tongs together and also to move them relatively to 40 each other.

24. In a buttoning machine the combination of a pair of tongs positioned side by side, constructed to embrace opposite sides of a button head and adapted to enter and 45 position a buttonhole for the buttoning operation, additional means arranged to engage the buttonhole fly and coöperate with said tongs in performing the buttoning operation, independent supports for said tongs, 50 a spreader arranged to engage said tongs, a support for said spreader, the supports for said tongs and said spreader having a telescopic engagement with each other, a cam mechanism connected with said spreader 55 support and arranged to cause the spreader to move the tongs apart to receive or release the button, and a cam mechanism for each of said tong supports arranged to move the tongs together relatively to said fly engaging means and to move them relatively to each other for tipping the button during 60 the buttoning operation.

25. In a buttoning machine the combination of button holding means, substantially 65 stationary means for engaging a button-

hole fly adjacent to the buttonhole during the buttoning operation, and mechanism for moving said button holding means for carrying the button head through the button-hole, said fly engaging means serving to resist the drag of the button on the button-hole fly during said buttoning operation.

26. In a buttoning machine the combination of substantially stationary means for engaging a buttonhole fly adjacent to a buttonhole during the buttoning operation, opposed button holding devices extending in front of said fly engaging means when in button receiving position, said devices being constructed to position the buttonhole 80 with the fly in operative engagement with said fly engaging means, and mechanism for operating said devices to cause them to carry the button head through the button-hole while the buttonhole fly is supported 85 by said fly engaging means against the drag of the button.

27. In a buttoning machine the combination of a pair of button holding tongs positioned side by side and lying in substantially 90 a horizontal plane, said tongs being constructed to enter and position a button-hole in a buttonhole fly when presented thereto in substantially a vertical plane, means adjacent to said tongs arranged to 95 engage the buttonhole fly during the buttoning operation, and mechanism for relatively moving said tongs and means to perform a buttoning operation.

28. In a buttoning machine the combination of button receiving means constructed and located to receive a button in position for the buttoning operation when the work is initially presented to the machine, and independent buttoning means constructed to 105 perform a buttoning operation on the work while it is held by the receiving means.

29. In a buttoning machine the combination of button receiving means constructed and located to receive a button in position 110 for the buttoning operation when the work is initially presented to the machine, and independent buttoning means constructed to perform a buttoning operation on the work and then to release the work while it is held 115 by the receiving means.

30. In a buttoning machine the combination of button receiving means constructed and located to receive a button in position for the buttoning operation when the work 120 is initially presented to the machine, and independent buttoning means arranged to perform a buttoning operation on the work while it is held by the receiving means, said receiving means and buttoning means being 125 mounted for relative movement toward and from each other.

31. In a buttoning machine the combination with buttoning means of work receiving means constructed and located to receive 130

- the work with a button in position for the buttoning operation when the work is initially presented to the machine, said work receiving means being mounted for movement with the buttoning means and constructed and arranged to maintain its engagement with the work during the buttoning operation.
32. In a buttoning machine the combination of work receiving means, buttoning means constructed to perform a buttoning operation on the work while it is held by the receiving means, and means for relatively moving the receiving and buttoning means to effect an initial presentation of the work to the buttoning means and to effect a discharge of the work from the buttoning means after the buttoning operation has been completed.
33. In a buttoning machine the combination of work receiving means adapted to position a button, buttoning means having provision for positioning a buttonhole for the buttoning operation, and mechanism for producing a relative movement of said buttoning means and receiving means to effect a presentation of the button to the buttoning means and for operating said buttoning means to effect a buttoning operation with respect to said button and buttonhole while said receiving means maintains its engagement with the work.
34. In a buttoning machine the combination of work receiving means adapted to position a button, buttoning means having provision for positioning a buttonhole for the buttoning operation, mechanism for producing a relative movement of said buttoning means and receiving means to effect a presentation of the button to the buttoning means and for operating said buttoning means to effect a buttoning operation with respect to said button and buttonhole, and means for moving said work receiving means to carry the work away from the buttoning means after the buttoning operation has been completed.
35. In a buttoning machine the combination of buttoning means, work receiving means mounted for movement toward and from said buttoning means, yielding means tending to maintain said receiving means in its work receiving position but permitting it to be moved therefrom, and mechanism for causing said buttoning means to perform a buttoning operation on the work while the work remains in operative engagement with the receiving means, said yielding means operating to return the receiving means to its initial position after the buttoning operation has been completed.
36. In a buttoning machine the combination of means for receiving a button for the buttoning operation, buttoning means comprising a pair of tongs, and mechanism for

operating said buttoning means to cause the tongs to grasp the button while it is held by the receiving means and to perform a buttoning operation with respect to said button.

37. In a buttoning machine the combination of means for receiving a button for the buttoning operation, buttoning means comprising a pair of tongs arranged to enter and position a buttonhole for the buttoning operation, and mechanism for operating said buttoning means to cause the tongs to grasp the button while it is held by the receiving means and to perform a buttoning operation with respect to said button.

38. In a buttoning machine the combination of a pair of button holding tongs having shank portions adapted to enter and position a buttonhole and additional portions constructed to hold a button head between them, buttonhole fly engaging means, mechanism for relatively moving said tongs and fly engaging means to effect a buttoning operation, and button receiving means positioned substantially in alignment with the direction of said relative movement and arranged to support the button for its initial presentation to the tongs.

39. In a buttoning machine the combination of buttoning means comprising a pair of button holding tongs and fly engaging means, a button receiving hook positioned in front of and in alignment with said buttoning means, and mechanism for operating said buttoning means to cause it to grasp the button held by said hook and to perform a buttoning operation with respect to said button.

40. In a buttoning machine the combination of a pair of button holding tongs having shank portions adapted to enter and position a buttonhole for the buttoning operation, and having additional portions constructed to hold a button head between them, means positioned adjacent to said tongs for engaging the buttonhole fly to cooperate with said tongs in performing the buttoning operation, a button receiving hook positioned in front of said tongs, said tongs being mounted for movement toward and from said hook, and a support for said hook mounted for movement in a path parallel to the direction of movement of said tongs.

41. In a buttoning machine the combination of a pair of button holding tongs lying in substantially a horizontal plane, buttonhole fly engaging means positioned adjacent to said tongs and arranged to cooperate therewith to perform a buttoning operation, and button receiving means positioned in front of said tongs and arranged to support a button with its head in position for its presentation to said tongs.

42. In a buttoning machine the combina-

tion of a horizontal series of buttoning instrumentalities, each comprising a pair of button holding tongs lying in substantially a horizontal plane, each of said pairs of 5 tongs being constructed to enter and position a buttonhole for the buttoning operation, a series of button receiving hooks positioned respectively in front of said pairs of tongs and each adapted to support a but-

ton for the presentation thereof to its co-operating pair of tongs, buttonhole fly engaging means, and mechanism for operating said instrumentalities substantially simultaneously to cause each pair of tongs to 10 grasp the button held by its co-operating hook and to perform a buttoning operation with respect to said button.

43. In a buttoning machine the combination of buttoning means, work receiving 20 means independent of said buttoning means and arranged to receive the work in position for the buttoning operation when the work is initially presented to the machine, said receiving and buttoning means being 25 relatively movable to effect a presentation of the work to the buttoning means, said receiving means being open for the introduction of the work in a direction transverse to the direction of said relative movement, 30 and operating mechanism for said buttoning means.

44. In a buttoning machine the combination of buttoning means, button receiving means, said receiving and buttoning means 35 being relatively movable to effect a presentation of the button to the buttoning means, and operating mechanism for said buttoning means, said receiving means having an upwardly inclined opening for the reception 40 of the button and being arranged to hold the button therein by gravity.

45. In a buttoning machine the combination of buttoning means, button receiving means opening upwardly for the reception 45 of the button, and operating mechanism for causing the buttoning means to engage a button held by the receiving means and to perform a buttoning operation with respect to said button.

50 46. In a buttoning machine the combination of a plurality of sets of buttoning instrumentalities, each set being adapted to perform a complete buttoning operation on the work, operating mechanism for causing 55 said sets to perform substantially simultaneously a plurality of complete buttoning operations, lazy tongs connecting said sets, and means for operating said lazy tongs to adjust the spacing of said sets relatively to each other.

47. In a buttoning machine the combination of a plurality of sets of buttoning instrumentalities, each set being adapted to perform a complete buttoning operation on 65 the work, said sets being mounted for rela-

tive movement toward and from each other, mechanism for operating said sets substantially simultaneously, a lazy tongs mechanism having its middle pivots connected respectively with said sets, and means for extending and contracting said lazy tongs mechanism to vary the spacing of said sets relatively to each other. 70

48. In a buttoning machine the combination of a series of sets of buttoning instrumentalities, each set comprising a pair of tongs, independent supports for said tongs, a spreader for said tongs and a support for said spreader, the supports for said tongs and spreader being mounted side by side for 75 movement in directions parallel with each other, a member connecting the like supports of all of the said sets together for common movement, and a cam for each series of said like supports operating through the said 80 respective connecting members to cause the tongs and spreaders of all the sets to be operated simultaneously.

49. In a buttoning machine the combination of a series of sets of buttoning instrumentalities, each set comprising a pair of tongs, independent supports for said tongs, a spreader for said tongs and a support for 90 said spreader, the supports for said tongs and spreader having a telescopic engagement with each other, means connecting the like supports of all the said sets together for common movement, and a cam for operating each series of said like supports to cause the tongs and spreaders of all the sets 95 100 to be operated simultaneously.

50. In a buttoning machine the combination of a plurality of sets of buttoning instrumentalities, each set being adapted to perform a complete buttoning operation on 105 the work, means for receiving work provided with a plurality of buttons, said means and sets being relatively movable to effect a presentation of the work to said sets, and mechanism for operating said sets substantially simultaneously, said receiving means having a plurality of openings for the reception of the buttons, said openings extending in directions substantially parallel with each other but transverse to the 110 direction of said relative movement of the receiving and buttoning means.

51. In a buttoning machine the combination of a plurality of sets of buttoning instrumentalities, each set being adapted to 120 perform a complete buttoning operation on the work, button receiving means having a plurality of upwardly inclined openings for receiving the buttons, and operating mechanism for relatively moving said receiving means and said sets to effect substantially simultaneously a presentation of the buttons to the buttoning instrumentalities and for causing said instrumentalities to perform substantially simultaneously a plurality of 125 130

buttoning operations with respect to said buttons.

52. In a buttoning machine the combination of means for performing a plurality of complete buttoning operations on work provided with a plurality of opposed buttons and buttonholes, said means being constructed and arranged to effect the entrance of each button edgewise into its opposed buttonhole, and mechanism for causing said means to perform said buttoning operations substantially simultaneously.

53. In a buttoning machine the combination of a plurality of sets of buttoning instrumentalities, each set being adapted to perform a complete buttoning operation and comprising buttonhole fly engaging means and button engaging means constructed to tip the button to present it edgewise to the buttonhole in the buttoning operation, and mechanism for operating said sets substantially simultaneously.

54. In a buttoning machine the combination of a plurality of sets of buttoning instrumentalities, each set being adapted to perform a complete buttoning operation and comprising means for giving the button a plurality of tipping movements during the buttoning operation, and mechanism for operating said sets substantially simultaneously.

55. In a buttoning machine the combination of a plurality of sets of buttoning means, each set being adapted to perform a complete buttoning operation, means for initially positioning a plurality of buttons for presentation to said sets of buttoning means, and mechanism for operating all of said sets together to effect substantially simultaneously a plurality of complete buttoning operations with respect to said buttons, each of said sets being constructed to tip the button during the buttoning operation to present it edgewise to the buttonhole.

56. In a buttoning machine, a pair of thin, opposed tongs constructed to enter a buttonhole and having portions shaped to embrace opposite sides of a button head, said tongs having shank portions overlapping each other, and means for spreading said tongs apart to enable them to receive or release the button.

57. In a buttoning machine, a pair of opposed tongs constructed to engage opposite sides of a button and normally positioned in substantially closed relation, said tongs being formed to present in their shank portions opposed converging surfaces, and a spreader movable lengthwise of the tongs and arranged to engage said surfaces to open the tongs to permit them to receive or release a button.

58. In a buttoning machine, a pair of opposed tongs of resilient material constructed

to engage opposite sides of a button and arranged in normally closed relation, said tongs having shank portions that extend inwardly toward each other, and a spreader movable lengthwise of the tongs and arranged to engage said shank portions to open the tongs.

59. In a buttoning machine, a pair of opposed tongs constructed to engage opposite sides of a button head to hold the button between them, said tongs having substantially flat button engaging portions formed with button receiving apertures and normally positioned close to each other in substantially parallel relation to facilitate positioning the tongs in a buttonhole prior to their engagement with a button.

60. In a buttoning machine, a pair of opposed tongs constructed to engage opposite sides of a button head, a device for engaging said tongs to spread their button engaging portions, means for operating said device to spread the tongs for the reception of a button and then to release them to permit them to close upon the button, means for effecting relative movement of the tongs and the buttonhole fly to cause the button to enter a buttonhole, and means for operating said spreading device to cause the tongs to release the button when the parts of the work are in buttoned relation.

61. In a buttoning machine, a pair of endwise movable tongs, means for engaging a buttonhole fly to position it with reference to said tongs, means for positioning a button fly with a button in line with the tongs, and means for operating the tongs to cause them to seize a button and draw it through the corresponding buttonhole.

62. In a buttoning machine, a pair of endwise movable tongs, means for engaging a buttonhole fly to position it with reference to said tongs, means for positioning a button fly with a button in line with the tongs, and means for operating the tongs to cause them to seize a button and draw it through the corresponding buttonhole including mechanism for effecting relative movement of the tongs to cause them to tip the button during the buttoning operation.

63. A buttoning machine having, in combination, buttoning means movable to effect a buttoning operation, and work receiving means constructed and located to receive and position a button in the path of movement of the buttoning means when the work is initially presented to the machine, said work receiving means being arranged to maintain its engagement with the work during the buttoning operation.

64. A buttoning machine having, in combination, a plurality of sets of operating instrumentalities, each comprising button receiving means and buttonhole fly engaging means, and mechanism constructed and ar-

ranged to effect relative movement of the receiving means and fly engaging means of each set to cause a plurality of buttoning operations to be performed on the work 5 while it is held by the said receiving means.

65. A buttoning machine having, in combination, buttonhole fly engaging means, a plurality of button engaging devices, and mechanism for operating said devices to 10 move a plurality of buttons toward said fly and cause said buttons to enter the corresponding buttonholes substantially simultaneously.

66. A buttoning machine having, in combination, buttonhole fly engaging means, work receiving means arranged to receive a plurality of buttons in position for buttoning operations, and buttoning means constructed and arranged to move said buttons 20 toward the buttonhole fly and cause the buttons to enter the corresponding buttonholes substantially simultaneously.

67. A buttoning machine comprising, in combination, work receiving means having a plurality of upwardly directed openings 25 for the reception of buttons, buttonhole fly engaging means, and buttoning means constructed and arranged to perform substantially simultaneously a plurality of button- 30 ing operations with respect to said buttons and the buttonhole fly.

68. In a buttoning machine, the combination of buttonhole fly engaging means, button engaging means, and mechanism for 35 moving said button engaging means in a direction transverse to the plane of the but-

tonhole fly to cause the button to enter a buttonhole.

69. In a buttoning machine, the combination of buttonhole fly engaging means, button engaging means, and mechanism for moving said button engaging means in a direction transverse to the plane of the buttonhole fly to cause the button to enter a buttonhole, said buttonhole fly engaging 45 means being constructed to resist the pressure of the button on the buttonhole fly during said movement of the button.

70. In a buttoning machine, the combination of buttonhole fly engaging means, work 50 receiving means arranged to present a button in a position opposite to a corresponding buttonhole in said fly, button head engaging means, and mechanism for operating said last named means to move the but- 55 ton toward the buttonhole fly and cause it to enter said buttonhole.

71. In a buttoning machine, the combination of button engaging means, work receiving means having an upwardly directed 60 opening for the reception of a button when the work is initially presented to the machine, and mechanism for operating said button engaging means to perform a buttoning operation with respect to said button. 65

In testimony whereof I have signed my name to this specification in the presence of two subscribing witnesses.

LEROY FARNUM.

Witnesses:

JOHN H. McCREADY,
WILLIAM B. KING.

Copies of this patent may be obtained for five cents each, by addressing the "Commissioner of Patents, Washington, D. C."

It is hereby certified that in Letters Patent No. 1,207,731, granted December 12, 1916, upon the application of Leroy Farnum, of Swampscott, Massachusetts, for an improvement in "Buttoning-Machines," errors appear in the printed specification requiring correction as follows: Page 5, line 91, claim 3, after the word "button" insert the word *head*; page 6, line 27, claim 10, after the word "means" insert the words *movable to grasp a button*; and that the said Letters Patent should be read with these corrections therein that the same may conform to the record of the case in the Patent Office.

Signed and sealed this 10th day of April, A. D., 1917.

[SEAL.]

F. W. H. CLAY,
Acting Commissioner of Patents.

Cl. 12—1.
